UNITED STATES PATENT OFFICE.

JOHN SULLIVAN, OF FALL RIVER, MASSACHUSETTS.

INCANDESCENT-ELECTRIC-LAMP SUPPORT.

No. 849,754.

Specification of Letters Patent.

Patented April 9, 1907.

Application filed October 24, 1906. Serial No. 340,321.

To all whom it may concern:

Be it known that I, JOHN SULLIVAN, a citizen of the United States, residing at Fall River, in the county of Bristol and State of Massachusetts, have invented a new and useful Improvement in Incandescent-Electric-Lamp Supports, of which the following is a specification.

This invention has reference to an improvement in electric-light fittings, and more particularly to an improvement in incandescent-electric-lamp supports.

In adjustably suspending incandescent electric lamps from the ceilings as has heretofore been done the flexible cord from the support to the lamp is carried down around a weighted pulley, then up around a pulley secured to the support, and then down to the lamp. In this construction the weighted pulley counterbalances the weight of the lamp, and the lamp is supposed to stay in the adjusted position through the friction of the cord and pulleys. As the lamp is raised or lowered for different positions the weight of the cord on the lamp side is decreased or increased, so that the lamp (particularly where long cords are used) cannot be accurately balanced by the weighted pulley. In practice I find that the usual jars or vibrations of a building will cause the lamp to move up or down from the position required, thus bringing the lamp into contact with the weighted pulley, which is liable to and does at times break the lamp under these conditions.

The object of my invention is to improve the construction of an incandescent-electric-lamp support whereby the lamp is adjustably suspended from the support and firmly held in the adjusted position.

A further object of my invention is to automatically hold the lamp in the adjusted position.

My invention consists in the peculiar and novel construction of an incandescent-electric-lamp support having details of construction whereby the lamp is adjustably suspended from the support and automatically held in the adjusted position, as will be more fully set forth hereinafter and claimed.

Figure 1 is a side view of my improved incandescent-electric-lamp support attached to a ceiling and showing the lamp adjustably secured to the support by a flexible cord and weighted pulley, with the lamp automatically held in the adjusted position. Fig. 2 is an enlarged face view of the support looking

from underneath. Fig. 3 is an enlarged vertical sectional view taken on line 3 3 of Fig. 2 through the support; and Fig. 4 is an enlarged vertical sectional view through the support, taken on line 4 4 of Fig. 2.

In the drawings, *a* indicates a support; *b*, a flexible cord in which are the usual wires; *c*, a weighted pulley, and *d* a common form of an incandescent electric lamp having the socket *e*, to which the wires in the cord *b* are attached in the usual way.

The support *a* is constructed, preferably, of porcelain and shaped to have the circular base *5* secured to the ceiling by screws 6 6 70 and merging into the raised central portion 7, in which is the cord-duct 8, the wire-ducts 9 9, leading to the usual electric-wire connections 10 10, and the approximately square off-center opening 11, extending through the 75 face to the back and having the oppositely-disposed wedge-shaped recesses 12 12, with the semicircular concave bottoms 13 13 in the end walls of the opening, as shown in Figs. 3 and 4, a filling member 14, constructed, preferably, of porcelain and shaped to have the base 15 with the arms 16 16 adapted to fit in the wedge-shaped recesses 12 12, and having the semicircular concave ends 17 17, which coincide with the semicircular bottoms 13 13 of the recesses 12 12. This member 14 is locked in the back of the opening 11 by the ceiling when the support is secured to the ceiling, as shown in Fig. 1. A shaft 18 extends across the opening 11 and 80 is supported at each end in the circular cavities formed by the semicircular bottoms 13 13 of the end recesses 12 12 and the semicircular ends 17 17 of the arms on the filling-piece 14, as shown in Figs. 3 and 4. A 85 shaft 18 is rotatably supported on the shaft 18 in the opening 11. This cam-pulley is constructed, preferably, of fibroid material and shaped to have an annular central groove 20 approximately one-half the 90 diameter of the pulley and the double semicircular cam-grooves 21 21 extending on each side from the bottom of the central groove 20 outward to the circumference of the pulley, as shown in Figs. 2 and 4, and in the direction that the pulley would revolve when the lamp is lowered.

The upper end of the flexible cord *b* is secured to the support *a* by passing the end through the cord-duct 8, the wires through the wire-ducts 9 9, and securing the ends of the wires to the connections 10 10, as shown

in Fig. 2, or the cord may be more firmly secured by knotting the cord at the intersection of the ducts. The lower end of the cord is now passed down under the weighted 5 pulley *c*, (which is sufficiently heavy to overbalance the weight of the lamp in any position of the lamp,) then up over the cam-pulley 19, and then down to the lamp, as shown in Fig. 1.

- 10 In the operation of my improved incandescent-electric-lamp support a short downward pull on the lamp *a* will release and bring the cord *b* into the central groove 20 of the cam-pulley 19, as shown in full lines in 15 Fig. 3. The lamp may now be adjusted vertically into the position required, when a side and an upward movement of the lamp will bring the cord into one of the cam-grooves 21 21, which will force the cord sidewise out 20 of the central groove 20 toward the circumference of the pulley, where, through the pull of the weighted pulley *c*, the cord is wedged between the bottom of the cam-groove 21 and the side walls of the opening 25 11 or the inner face of the filling member 14, as shown in broken lines in Fig. 3, and the lamp when released is held securely in the adjusted position, as shown in Fig. 1.

It is evident that the construction of the 30 support could be varied so that a double cord could be used, if desired, without materially affecting the spirit of my invention.

Having thus described my invention, I claim as new and desire to secure by Letters 35 Patent—

1. A lamp-support embodying a base formed with an opening which extends through the top and bottom of said base, two of the side walls formed by said opening being formed with recesses which extend from the top of said base downwardly to points at a slight distance from the bottom of said base, said recesses terminating in semicircular bottoms, a pulley-carrying shaft en-

gaging in said semicircular bottoms, and a 45 filling member having a base of approximately the same width as the distance between said recesses of the side walls and depending arms which seat in said recesses to directly overlie and engage said shaft ends. 50

2. An incandescent-electric-lamp support comprising a base having a raised central portion formed with a cord-duct and with wire-ducts which lead into said cord-duct, wire connections disposed at the outer ends 55 of said wire-ducts, said base being formed with an off-center opening, two of the walls formed by said opening being formed with wedge-shaped recesses terminating in semicircular bottoms, a filling member having a 60 base closing the top of said opening and arms shaped to fit in said recesses and provided with semicircular concave ends coinciding with said concave bottoms of said recesses, a shaft extending across said opening and having its ends extending in said semicircular portions of the recesses and said ends of said arms, and a pulley on said shaft. 65

3. A lamp-support embodying a base formed with an opening extending through 70 the top and bottom of said base, two of the opposing walls formed by said opening being formed with vertical recesses terminating in shaft-seats which latter are disposed intermediate the top and bottom of said base, a 75 filling member having a base at the top of the opening and formed with depending arms to slide in said recesses of the side walls and have their lower ends overlie the shaft-seats and engage the shaft. 80

In testimony whereof I have signed my name to this specification in the presence of two subscribing witnesses.

JOHN SULLIVAN.
